UNITED STATES PATENT OFFICE.

FREDERICK MENZER, OF FLINT, MICHIGAN.

CARRIAGE-BODY.

SPECIFICATION forming part of Letters Patent No. 664,090, dated December 18, 1900.

Application filed July 13, 1900. Serial No. 23,451. (No model.)

To all whom it may concern:

Be it known that I, FREDERICK MENZER, a citizen of the United States, residing at Flint, county of Genesee, State of Michigan, have 5 invented a certain new and useful Improvement in Carriage-Bodies; and I declare the following to be a full, clear, and exact description of the invention, such as will enable others skilled in the art to which it pertains to make 10 and use the same, reference being had to the accompanying drawings, which form a part of this specification.

My invention relates to improvements in vehicle-bodies; and its object is to provide for 15 a simple, convenient, and easy manner of changing from a single to a two seated body and also to accommodate a canopy-top to such change; and it consists in the arrangements and combinations hereinafter described and 20 claimed.

Reference being had to the accompanying drawings, Figure 1 is a perspective view of the body arranged for a single seat with the canopy thereon. Fig. 2 is a perspective of the 25 body and canopy arranged for a two-seated rig. Fig. 3 is a longitudinal sectional view of the body arranged for one seat. Fig. 4 is a longitudinal sectional view of the body arranged for two seats. Fig. 5 is a plan view 30 of the body arranged for one seat. Fig. 6 is a plan view showing a body arranged for two seats. Fig. 7 is a view from the under side of the arrangement, showing the canopy when changed from a single to a double seated body.

35 In the drawings, A represents the body proper.

B is a seat which, as hereinafter explained, is shifted from the rear end to nearly the central point of the body or the reverse, as required, it being used as a single-seated vehicle when shifted to the front end, or it is used as the rear end of a double-seated body.

C is a folding seat used in front.

D is one portion of the canopy-top, which 45 is used with the seat B. E is another portion which is used only when the seat C is used and in conjunction with the top D.

The top of the body is constructed in such 50 form that the seat B can be slidably engaged therewith and shifted from the position shown in Fig. 1 to the position shown in Fig. 2 or the reverse. It is unnecessary to describe the

details of this feature of construction so far as a sliding adjustment is concerned, as they are old and well known, and the exact mode 55 of adjustment is not in itself a feature of this invention, which is not confined to the means whereby the seat is made to slide, as any means permitting the seat to be slidably attached to the body A would be within this invention. 60

The seat B may be of the ordinary construction with the exception of means for holding the canopy-top B, as shown. This consists of sockets b b, attached to the back of the seat, and also brackets b', attached to the arm or 65 side of the seat.

With respect to the position of the forward seat C the body A is peculiarly constructed. Two standards a a are rigidly attached to the framework of the body A. The side pieces 70 a' are also rigidly attached, one of which is shown in each of Figs. 1 and 2, and flaring arm rests or rails a² are also rigidly attached to the body A. As shown in Figs. 5 and 6, the standards a, the pieces a', and 75 bows or arm-rests a² are transversely wider than the length of the seat B, so that the seat B when brought forward, as shown in Fig. 1, telescopes between the pieces a' and arm-rests a² and standards a. It is obvious how these 80 pieces can be attached to the body A, and it is sufficient, therefore, to merely say that they are rigidly attached by any convenient means. It is obvious that when the seat B is moved in the position shown in Fig. 2 the 85 parts marked a a' a² remain in position and, in effect, as will hereinafter be seen, form a part or act in conjunction with the seat C when it is in position. The seat C is so constructed that when not in use it may be 90 folded down upon steps F, located in the bottom of the body, and is thus entirely out of the way, the seat B being drawn forward over it. The seat, &c., consists of a framework comprising two side pieces c, one on 95 either side of the body, as shown in an elevated angular position in Fig. 2, and which are hinged at c' to blocks c², rigidly fastened to the body of the carriage. A framework c³, forming a seat-bottom, is pivotally attached to the framework c at c⁴. The framework c³ may be upholstered with springs in the usual manner, and this framework, as will be observed in Figs. 5 and 6, forms the bot-

100

tom of the seat when in place. Another frame upholstered as may be desired and marked c^5 is pivoted to the rear edge of the seat c^3 at c^6 above the pivot c^4 , folds forward 5 upon said seat, and when opened upward forms a back to the seat when in place, as in opening it upward the lower edge of this back c^5 comes in contact with the rear edge of c^3 at c^7 , which prevents the further rotation and makes the back rigid. It will be observed that this seat c^3 thus formed has no arms, but that the fixed elbow - rests $a^2 a^3$ 10 form the arms to the seat when elevated, as in Fig. 4.

15 In the body there is permanently attached a cross - bar a^3 , upon which rests the front edge of the bottom of the seat c^3 . A pair of hooks $c^8 c^8$ are firmly attached to the bottom of the seat c^3 , and which engage the cross-bar a^3 and extend downward in front of said bar and backward under said bar, preventing all 20 backward and upward movements of the seat when in position as in Fig. 4. One or more buttons c^9 are also attached to the framework 25 c^3 , which are adapted to engage with the bar a^3 , and when so engaged they prevent all forward motion of the seat. The frame c is so hinged to the carriage-body and to the seat C that when said seat is in its raised position 30 the frame c slants backward from the floor upward, so that the weight upon said seat and said frame tends to draw the seat backward and to engage the hook c^8 more forcibly against the bar a^3 . The mode of operation of this 35 construction is quite obvious. When not in use, the parts of the seat C are folded down, as shown in Fig. 3. When it is desired to use the seat, they are elevated, rising on the pivots c . The forward edge of the frame or 40 seat-bottom c^3 is brought forward far enough to enable the hooks c^8 to engage the cross-bar a^3 , and when they are so engaged the button c^9 is turned so as to engage the rear of the 45 cross-bar a^3 , and the rest C is thus firmly held, the front edge being supported by the cross-bar and the rear edge by the two supports $c c$. The back c^5 is then lifted up to the position 50 shown in Fig. 4 and the seat is completed, with back-rest and arm-rests. When in this position, the seat B is simply moved back to the rear end of the body, and it thus forms a two-seated vehicle. When it is desired to 55 change it to a one-seated vehicle, the button c^9 is rotated out of contact with the cross-bar a^3 , the seat slightly moved forward to disengage the hooks, the back folded down, and the seat dropped by the swinging of the supports c backward and downward until they 60 are folded up in small compass in the bottom of the carriage-body. The seat B is then slid forward to take the place of the seat C and the change is completed. In order to adjust a canopy-top to this form of construction, I provide, as already stated, a canopy-top D 65 for the seat B, and which is composed of a top D', supported by four standards $d d' d' d'$. These enter sockets $b b' b' b'$, permanently at-

tached to the back and sides of the seat. The standards d and d' are pivoted at their points of conjunction or connection with the top, so 70 that they may be folded up against the top, if desired, and also to allow motion to detach the top from the seat. Its position is shown in Fig. 1 when the single seat is used. When a double seat is used, the canopy - top D is 75 supplemented by that of E, which consists of two parts $e e'$, hinged together at e^2 . Pivotally attached to the part e' are two standards $e^3 e^3$, which are adapted to engage in permanent sockets e^4 , permanently attached to the 80 back c^5 of the seat C. Upon the part e there are also pivoted two standards $e^6 e^6$, the lower ends of which are bent at right angles at $e^7 e^7$, as shown in Fig. 7, and engage eyes e^8 , formed 85 in the top of the standards $a a$.

It is obvious that the canopy-top e and e' may be attached to the seat C by the attachments just described. The rear edge of that portion e' of the top is connected to D' by lugs $d^4 d^4$ engaging in mortises $d^5 d^5$ on the top 90 F and held therein by a button d^6 , especially as shown in Fig. 7. This form of construction for the canopy-top I intend to cover in a separate application. It is obvious, therefore, that when in position, as shown in Fig. 95 2, by turning the button e^4 can be detached from D', the standards e^3 and e^6 can be lifted out of their sockets, and e folded upon e' , the standards also folding down. The seat C can be folded as already described and the canopy 100 formed to go with it deposited in the bottom of the carriage - body. The seat B and its canopy may be moved forward to take the position and assume the appearance as shown in Fig. 1. The arm-rests $a^2 a^2$, combined with 105 the arm of the seat C, are not only wide enough to permit the seat B to telescope between them, but they afford a wide front seat when the seat C is in position, and this is a 110 peculiar advantage obtained by my construction.

When the seat B is moved forward, the rear portion of the bottom may be covered by a boot in the usual manner by buttons, but which may be detached when the seat is moved 115 to the rear and folded up and placed in any convenient receptacle.

What I claim is—

1. In a vehicle, a body portion, a sliding seat arranged to operate in connection therewith, an auxiliary seat consisting of seat portion and a back portion hinged thereto, double standards supporting the rear portion hinged thereto and to the bottom of the body, a cross-bar attached to the body supporting the front 120 of the seat, means upon the seat portion for attaching and detaching the seat portion from the cross-bar, substantially as described.

2. In a vehicle, a body portion provided with standards a, a , extending upward from the side thereof at the forward part of that part of the body at which the forward seat is to be located, rails a^2 , secured to said standard and to the vehicle-body, an auxiliary seat 130

adapted to be folded upon the bottom of the carriage, a sliding seat arranged to operate in connection with the vehicle-body, each of said seats being adapted to be placed between 5 said standard and arms, and said standard and arms being adapted to form the arm-rests of the seat placed between them, substantially as described.

3. In a vehicle, a body portion, a cross-bar 10 a^3 , upon said body portion, a folding seat C, said seat being provided with hinged braces c, so located that they shall have a backward slant when the seat is in position, said seat being provided with a hook c^8 , extending vertically 15 in front of said cross-piece, and bending backward under said cross-piece, substantially as and for the purpose described.

4. In a vehicle-seat, the combination of the horizontal part c^3 , means for supporting the 20 front of said horizontal part, the braces c, hinged to the back and under part of the part c^3 , and to the vehicle, and a back c^5 , hinged

near the upper surface of the part c, so as to be adapted to fold forward upon the part c^3 , and to be held in its proper working position 25 by coming into contact with said horizontal part, substantially as described.

5. In a vehicle, the combination of a body provided with a cross-piece a^3 , a seat consisting of a horizontal part c^3 , the front resting 30 upon said arm-piece, a hook a^8 , secured to the part c^3 , extending in front of, and under said cross-piece, a brace c, hinged to the back of the part c^3 , and to the body so as to slant backward, and a back c^5 , hinged at the near 35 edge of the part c^3 , so as to be adapted to fold over upon said part, and coming into contact with the part c^3 , substantially as described.

In testimony whereof I sign this specification in the presence of two witnesses.

FREDERICK MENZER.
